R. J. KEHL
BLOWPIPE NOZZLE

Filed June 11, 1921

UNITED STATES PATENT OFFICE.

ROBERT J. KEHL, OF CHICAGO, ILLINOIS, ASSIGNOR TO OXWELD ACETYLENE COMPANY, A CORPORATION OF WEST VIRGINIA.

BLOWPIPE NOZZLE.

Application filed June 11, 1921. Serial No. 476,858.

This invention relates to blowpipe nozzles and particularly to a multiple flame nozzle adapted for use with machine-welding blowpipes, but it will be understood that the principles of the invention may be utilized in other types of blowpipe nozzles.

Multiple flame nozzles as heretofore constructed have been provided with substantial 5 parallel outlet passages formed by "straight drilling" into the nozzle body. The flames from the orifices of a nozzle of this type are blunt and in welding operations spread over a comparatively wide area on opposite sides of the line of weld, resulting in 10 dissipation of heat and uneconomical use of gas. In a nozzle of this type, moreover, all 15 of the orifices are always open, whereas, for different classes of work, it is desirable at times to use less than the total number of 20 orifices, or orifices varying in size or arrangement.

One of the objects of this invention is to provide a multiple flame nozzle in which the outlet gas passages are constructed to develop 25 comparatively long tapering and pointed flames, the points of which may be more closely confined to a given portion of the weld.

Another object of the invention is to provide 30 a multiple flame nozzle which will allow a choice of orifice arrangement, i. e., a variation of the orifice size; a choice of the location, relative distance from the weld, and number of orifices in use.

Another object is to provide a nozzle in 35 which the parts may be easily and economically interchanged, adjusted and replaced, thereby permitting a wide heating range from a single nozzle.

The above and other objects and the novel 40 features of the invention will be apparent from the following description taken in connection with the drawing, in which

Fig. 1 is a sectional view of a multiple flame 45 nozzle embodying this invention, showing the same connected to a gas mixing device,

Figs. 2 and 3 are sectional views of other 50 multiple flame nozzles embodying the present invention,

Figs. 4 and 5 are side elevational views of other nozzles embodying the present invention, illustrating different orifice arrangements, and

Figs. 6 and 7 are, respectively, a longitudinal 55 sectional view and an end elevational view

of another nozzle embodying the present invention.

Generally speaking, a tapering or conical flame having a pointed end is desirable because the heat thereof may be directed approximately along the line of weld and by thus confining the heat, a more economical operation is obtained. A nozzle constructed so as to produce flames of this type is illustrated in Fig. 1 in which the unitary body or casting C is provided with a longitudinally extending main gas passage G. The main gas passage communicates with and distributes the mixture to a series of parallel gas passages, portions of which taper toward 60 or to a point adjacent their orifices, whereby tapering flames are produced. The casting C is elongated, being of such length that it projects considerably beyond one side of the outline of the mixer M to which it is coupled, 65 so that the orifices therein may be distributed 70 a distance along the seam to be welded.

In the particular arrangement shown in Fig. 1, the tapering gas passages A are formed in tips T which may be detachably 75 connected to the nozzle body, as by threaded stems T' thereon adapted to screw into the threaded holes H which communicate with the main gas passage G. The threaded holes H may be formed by "straight drilling" relatively 80 large holes and tapping the same. In the nozzle illustrated in Fig. 2 an equivalent construction is shown in which the body C' has externally threaded hollow studs h to fit in the internally threaded ends t' of the tips 85 t which have tapering passages a. The lower side of the nozzle body may be of stepped formation, providing a series of steps B, into the faces of which the holes H, h are drilled, the axes of said holes desirably being parallel 90 to one another and oblique to the axis of the main gas passages G, so that the orifices R or r of the tips may be approximately the same distance from the main passage G.

A complete blowpipe includes a mixing 100 device M coupled to the inlet end of the nozzle casting, as by a suitable nipple N and bushing J, shown in Fig. 1, or by a threaded nipple N', as shown in Fig. 2. The nipple N is screw-threaded to fit into the threaded inlet opening I, the nipples N, N' discharging into one end of the main gas passage G, which tapers slightly and may be formed by drilling a hole longitudinally into the casting and plugging the same, as at L. 105 110

As already indicated, by providing a set of interchangeable tips, of suitable metal such as copper, brass or bronze, which may be screwed onto the nozzle body, variations of the tip arrangement may be effected, as is shown, for example, in Figs. 1 and 4, wherein tips of different size are arranged in the holes at the opposite ends of the nozzle casting. Other or similar tips could be screwed in 5 of the intermediate holes H, as illustrated for example in the nozzle shown in Fig. 4, but for the purpose of illustrating another advantage of this type of nozzle the intermediate holes are shown as closed off by suitable plugs P, having screw-threaded stems P' fitting the threaded holes H. Both the tips and the screw plugs may have suitable means, such as the hexagon portions shown, to facilitate tightening and removing them 10 with a wrench or other tool. Similarly, cup-shaped internally threaded plugs or caps p may be provided to close off outlets of the nozzle body shown in Fig. 2. Several sets of tips of different sizes may be provided for 15 each nozzle to permit of a variation in the sizes of tips used and a set of plugs may be furnished with each nozzle so that the positioning and arrangement of the tips may be widely varied as desired. Fig. 5, for example, shows another variation in the arrangement of the tips and plugs. Collars or washers W may be placed at the shoulder of the tips or different length tips may be used to 20 locate the flames at desired different distances from the weld, as illustrated in Figs. 1, 2 and 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

Where the work performed by a given nozzle, for example on a machine-welding blowpipe, requires only one size and arrangement of flames, another type of multiple flame nozzle embodying the present invention may be employed, in which the flames from the orifices are tapering and pointed but in which the orifices and the tapering passages thereto are directly formed in the casting, as illustrated for example, in Fig. 3. In this arrangement, the tapering passages H' communicate with the main gas passage G' and may be formed directly in the casting by drilling. In order to taper these passages downwardly toward their orifices R' adjacent the stepped lower side of the casting, tapering drills are inserted through holes V in the upper side of the casting opposite the tapering passages H'. The end passage H'' opposite the gas inlet may be drilled to a taper by inserting the tool through the nipple N'. When the tapering passages have been completed, the holes V may be closed, as by brazing in a plug as shown. In this arrangement of course, all of the tapering passages supply gas jets during the operation of the blowpipe

and as the number or arrangement of jets may not be readily varied, the type of nozzle construction shown in Figs. 1, 2, 4 and 5 is the more desirable one for general welding purposes. When in use on a machine-welding blowpipe the nozzle is desirably adjusted so that the series of jets or flames impinge on the work X at an oblique angle along a given seam to be welded.

The nozzle shown in Figs. 6 and 7 also embodies this invention and in this construction the main gas supply passage I'' has several passages i, i' and i'' branching therefrom, comprising one or more threaded parts having tapered tips T detachably coupled thereto. The passages i and i'' are oblique to the axis of the passage I''. The gase supply passage I'' is within a threaded nipple N' by means of which the nozzle may be coupled to the mixing device of a blowpipe. Means, such as a collar Z having opposite flat faces, may be provided to facilitate the use of a wrench in coupling and uncoupling the nozzle and gas supply device or mixer. Suitable plugs and tips may also be supplied to be interchangeably coupled to the body C' of this nozzle so that the flame arrangement may be readily varied as desired.

While the improved nozzles and blowpipes are shown and described in detail, it is to be understood that modifications may be made therein without departing from the principles of the invention or sacrificing any of its advantages.

I claim:

1. A multiple flame blowpipe nozzle comprising a main gas passage, a series of outlet passages branching from said main passage, and tips and plugs having portions adapted and arranged to removably and interchangeably fit said outlet passages whereby the orifice arrangement of the nozzle may be varied.

2. A multiple flame blowpipe nozzle comprising a main gas passage, a series of outlet passages branching from said main passage, and plugs having portions adapted and arranged to removably and interchangeably fit the ends of said outlet passages whereby the orifice arrangement of the nozzle may be varied.

3. A multiple flame blowpipe nozzle comprising a main gas mixture passage, a series of outlet passages branching angularly from said main passage and threaded near the ends thereof; and a set of tips and plugs adapted and arranged to removably and interchangeably fit said outlet passages whereby the outlet orifice arrangement of the nozzle may be readily varied as desired; each tip having a longitudinal passage tapering toward its orifice, a threaded part adapted to fit any one of said threaded passages and means engageable by a suitable tool to facilitate tightening and removing the same; each plug having a threaded part adapted to fit any one of

said threaded passages, and means engageable by a suitable tool to facilitate tightening and removing the same.

4. A multiple flame blowpipe nozzle comprising a casting having a stepped lower side and a main gas passage, a series of threaded outlet passages branching from said main passage and severally terminating in the steps

on the lower side of said casting, and tips and plugs having threaded portions adapted and arranged to removably and interchangeably fit said threaded outlet passages, whereby the orifice arrangement of the nozzle may be readily varied as desired.

In testimony whereof, I affix my signature.
ROBERT J. KEHL.
